US0D1053125S

(12) **United States Design Patent** (10) **Patent No.:** **US D1,053,125 S**
(45) **Date of Patent:** **** Dec. 3, 2024**

(54) **CHARGING STATION FOR ELECTRIC VEHICLES**

(71) Applicant: **Dover Fueling Solutions UK Limited**, Edinburgh (GB)

(72) Inventors: **Mattias Mårtensson**, Kävlinge (SE); **Marlene Wemmert**, Löddeköpinge (SE)

(73) Assignee: **Dover Fueling Solutions UK Limited**, Edinburgh (GB)

(**) Term: **15 Years**

(21) Appl. No.: **29/914,642**

(22) Filed: **Oct. 19, 2023**

Related U.S. Application Data

(62) Division of application No. 35/514,702, filed on May 23, 2022 (U.S. filing date under 35 U.S.C. 384), and having an international filing date of May 23, 2022.

CLAIM

The ornamental design for a charging station for electric vehicles as shown and described.

DESCRIPTION

FIG. 1 is a front perspective view of a charging station for electric vehicles;

FIG. 2 is a rear perspective view thereof;

FIG. 3 is a front view thereof;

FIG. 4 is a rear view thereof;

FIG. 5 is a left view thereof;

FIG. 6 is a right view thereof; and,

FIG. 7 is a top view thereof.

The broken lines shown in the drawings are for the purpose of illustrating portions of the charging station for electric vehicles that form no part of the claimed design.
